US00D849490S

(12) **United States Design Patent** (10) **Patent No.:** **US D849,490 S**
Dubiel et al. (45) **Date of Patent:** **** May 28, 2019**

(54) **IRRIGATION INJECTOR**

(71) Applicant: **Chapin Manufacturing, Inc.**, Batavia, NY (US)

(72) Inventors: **David Dubiel**, N. Chili, NY (US); **Edward Horeth**, Rochester, NY (US)

(73) Assignee: **Chapin Manufacturing, Inc.**, Batavia, NY (US)

(**) Term: **15 Years**

(21) Appl. No.: **29/625,318**

(22) Filed: **Nov. 8, 2017**

(51) LOC (11) Cl. **08-01**

(52) U.S. Cl.

USPC **D8/1**

CLAIM

The ornamental design for the irrigation injector, as shown and described.

DESCRIPTION

FIG. 1 is a front perspective view of an irrigation injector of our new design shown in environment;

FIG. 2 is a front perspective view of an irrigation injector of our new design;

FIG. 3 is a left side view thereof;

FIG. 4 is a right side view thereof;

FIG. 5 is a front view thereof;

FIG. 6 is a back view thereof;

FIG. 7 is a top view thereof; and,

FIG. 8 is a bottom view thereof.

The broken lines in FIG. 1 are for purposes of illustrating environmental structure and form no part of the claimed design.

1 Claim, 5 Drawing Sheets
